I. J. SHORT.
SELF ADJUSTABLE WRENCH.
APPLICATION FILED JUNE 13, 1919.

1,332,922.

Patented Mar. 9, 1920.

UNITED STATES PATENT OFFICE.

IRA J. SHORT, OF ARCHBOLD, OHIO.

SELF-ADJUSTABLE WRENCH.

1,332,922.

Specification of Letters Patent. Patented Mar. 9, 1920.

Application filed June 13, 1919. Serial No. 303,893.

To all whom it may concern:

Be it known that I, IRA J. SHORT, a citizen of the United States of America, residing at Archbold, in the county of Fulton and State 5 of Ohio, have invented certain new and useful Improvements in Self-Adjustable Wrenches, of which the following is a specification, reference being had therein to the accompanying drawing.

10 This invention relates to self adjusting wrenches and has for its object the production of a simple and efficient means for causing the adjustable jaw to automatically adjust itself around a nut, pipe or other device 15 which it is desired to grip by means of the wrench.

Another object of this invention is the production of a simple and efficient means for holding the pressure spring in engagement 20 with the adjustable jaw supporting links.

A still further object of this invention is the production of simple and efficient means for supporting the gripping plates in engagement 25 with the respective jaws.

In the drawings:—

Figure 1 is a side elevation of the wrench.

Fig. 2 is a plan view of the back portion of the wrench.

30 Fig. 3 is a vertical section through the jaws of the wrench.

Fig. 4 is a section taken on line 4—4 of Fig. 3.

Fig. 5 is a detail perspective view of the 35 jaw of the wrench.

Fig. 6 is a perspective view looking at the rear face of the gripping plate carried by the adjustable jaw.

By referring to the drawings it will be 40 seen that 1 designates the handle of the wrench which comprises a stationary jaw 2, which jaw 2 is provided with an elongated notch 3 upon its inner face and a cut-out portion 4 within which cut-out portion 4 fits 45 the gripping plate 5 of the stationary jaw.

This gripping plate 5 is provided with a plurality of gripping teeth 6 upon the inner face of the plate 5 for firmly gripping or biting into a nut or other objects notched 50 thereby. This plate 5 is provided with an inwardly extending rib 7 which rib 7 fits within the groove 3 formed in the jaw 2 and is firmly held therein by means of the rivets 8.

55 The shank or handle 1 is provided with a link receiving channel or groove 9 upon its

inner face and a primary link 10 and an auxiliary link 11 is pivotally mounted within the groove 9 upon the pivot pins 12 and 13 respectively.

60

An adjustable jaw 14 is pivotally secured to the links 10 and 11, these links fitting within the groove or notch 15 formed upon the inner face of the adjustable jaw 14. This adjustable jaw 14 is provided near its 65 outer end with a groove or notch 16 within which groove or notch 16 fits a rib or tongue 17 of the gripping plate 18. The forward end of the plate 18 is thickened and rests against the shoulder 19 formed in the adjustable jaw 14 thereby relieving considerable strain from the securing pin 20. The plate 18 is provided with a longitudinally extending slot 21 to permit the link 10 to work freely within the channel or slot 15 70 and also to permit a wide gripping face to be had upon the plate 19 when the jaw is in a forwardly or outwardly swung position.

A compressing spring 22 is carried by the 80 handle 1 and is provided with a coiled-portion 23 fitting snugly within the notch or groove 9. The inner end 24 of the spring 22 is firmly seated within a socket 25 in the handle 1 and a transversely extending 85 anchoring pin 26 passes through the handle 1 and through the looped portion or coil 23 of the spring 22 thereby holding the spring 22 within the channel or groove 9. The coiled-portion 23 of the spring 22 fits snugly 90 within this channel or groove 9 and is thereby held against any loose swinging or tilting movement within the channel or groove 9. The coiled-portion 23 of the spring 22 however is sufficiently loose within 95 the channel or groove 9 to permit the spring 22 to unwind or wind upon this coiled-portion 23. The pin 26 also is sufficiently loose to permit the coil spring to slide there-around. The spring 22 is provided with a 100 forwardly extending portion 27 which terminates in an upwardly and outwardly extending portion 28, this upwardly and outwardly extending portion 28 formed in a laterally extending portion 29.

105

What is claimed is:—

1. A wrench comprising a stationary jaw, an adjustable jaw, links connecting said adjustable jaw with said stationary jaw, said stationary jaw provided with an elongated 110 slot, a coil spring placed within said elongated slot and projecting therefrom, said

coil spring provided with a forwardly extending portion terminating in a laterally extending end, said laterally extending end engaging one of said links and urging the same forwardly.

2. In a wrench of the class described, the combination of a handle provided with an integral stationary jaw, said jaw provided with a central, longitudinally-extending 10 socket formed in its inner edge, a pair of links having a set of ends positioned down in said socket, fastening means extending through the jaw and said links within the socket fastening the links to the jaw, an adjustable jaw provided with a longitudinally-extending groove, said links having one set of their ends in said groove of the adjustable jaw, means fastening said last-mentioned ends in said groove, a spring provided with 20 a coil and with an outer free end bearing directly against the rear edge of one of the links, said coil of the spring positioned entirely within the longitudinally-extending socket of the first-mentioned jaw, and means 25 in said socket fastening the spring therein,

said positioning of the coil entirely within said socket preventing wabbling of the spring and displacement of its outer free end off the back edge of the link, substantially as shown and described.

3. A wrench comprising a stationary jaw, an adjustable jaw, means for connecting said adjustable jaw with said stationary jaw, said adjustable jaw provided with a shoulder formed thereon, a gripping plate carried by 30 said adjustable jaw and engaging said shoulder, said gripping plate provided with a rib formed upon the under face thereof, said adjustable jaw provided with a socket formed therein for receiving said rib, said stationary jaw provided with a groove, a spring provided with a coil-portion seated within said groove for holding said spring from tilting, and said spring provided with 35 means for engaging said adjustable jaw and 40 forcing the same forwardly.

In testimony whereof I hereunto affix my signature.

IRA J. SHORT.
